OF CHICAGO, ILLINOIS, A CORPORATION OF ILLINOIS.

DUMP-CAR ATTACHMENT.

1,074,994.

Specification of Letters Patent.

Patented Oct. 7, 1913.

Application filed August 24, 1911. Serial No. 645,790.

To all whom it may concern:

Be it known that I, HOWARD VAN SCY, a citizen of the United States, residing at 6425 Peoria street, Chicago, Illinois, have invented certain new and useful Improvements in Dump-Car Attachments, of which the following is a specification.

This invention is an attachment for use in connection with dumping-cars of the sort having inclined side-doors capable of swinging outward and upward, and which allow the material therein contained to slide out by gravity.

It is well known that, in cars of the kind referred to, the drop doors, which the dumped material causes to swing out at first, will immediately rebound and obstruct the discharge by flapping back against such portion of the material as remains yet to be unloaded, thereby making it difficult to unload a car completely without subjecting the attendant to the trouble of holding the door open, or of reopening it several times to clear the outlet and work off the load, with consequent waste of time and inconvenience.

The present invention aims to obviate the trouble thus experienced with the dumping-cars, and other vehicles, structures, or receptacles that are unloaded in a like manner, by providing means whereby the discharging valve or door thereof is kept out of the way of the dumped material from the start, that is to say remains wide open from the moment it is pushed out, so that no obstacle whatever is offered to an immediate, complete discharge.

Referring to the accompanying drawing, which forms an inseparable part hereof, and in which corresponding numerals are used to designate similar elements throughout the several views,—Figure 1 is a cross sectional elevation of a dumping car of known design to which the invention has been applied, the same having doors on both sides, one of which is shown closed, and the other partly open. Fig. 2 is a fragmentary view, reproducing the upper right-hand side of Fig. 1, but showing the door on that side opened to its full extent. Fig. 3 is a detached rear view of a portable hook-bar constituting the principal part of the invention, and shown in side elevation in the preceding figures.

Among other elements, which it is unnecessary here to mention, the car represented in Fig. 1 includes the following, viz:

a hopper or equivalent receptacle 1, having sides 2 and 3 inclined inwardly and downwardly; similarly-inclined drop doors 4 and 5, hinged so as to hang from the said sides; a normally V-shaped bottom composed of 60 tilttable halves 6 and 7, disposed in the same planes as said doors respectively, acting as detent retainers therefor to maintain them in their closed positions, and coacting therewith in keeping the material within the 65 hopper; discharge aprons composed of fixed outer sections 8, 9, and movable inner sections 10, 11, adapted to lead the dumped material down either outside or inside the track along which the car runs; and rocking 70 detents 12, 13, operated by shafts 14, 15, and engaging triangular supports 16, 17 of the V-shaped trough, whereby either half, 6 or 7, of the latter can be dropped or tilted so as to release the door, 4 or 5, retained thereby, 75 and lie in one continuous incline with the other half of said trough and the closed door on the opposite side, thus allowing the material to slide down and out, either to the right or left, according to which side door 80 was released and dropped. The above enumerated parts are common in that type of car, and consequently no claim is made to them herein, save in so far as the combination thereof with the novel elements of the 85 invention, about to be described, is concerned.

The means provided for keeping the drop door wide open as intended is automatic, and in the preferred form of the invention, 90 consists of a portable bar 18, having hooks 19, 20, at the ends, that is one hook on each end. These hooks are made to engage, respectively, the side of the hopper or receptacle 1 directly above the drop door, and the lower edge of the door itself as it is swung open. At first the bar 18 is located so that the upper hook 19 thereof will cause it to hang from the hopper in the manner represented on the left-hand side of Fig. 1, and each side of the receptacle may, if desired, be thus supplied with a bar having such hooks. The engagement of the lower-hook 20 with the drop door is effected by impact of the latter against the former, as suggested 95 in Fig. 2, where for example the right-hand side door 5 is shown as being swung open and encountering the pendent hook of the adjacent bar. The door repels the bar as it meets the hook thereof, but at the same time 100 105 110

it swings up past the point of the hook and is caught thereby, as Fig. 2 indicates, before it could rebound back against the side of the hopper or the material therein that 5 remains to be dumped. The hook thereafter retains the door in its open position, until released, meanwhile keeping the outlet of the hopper free from impediment and permitting the contents thereof to be emptied 10 continuously at one operation without stoppage. Sufficient weight is imparted to the bar 18 to enable it always to come seasonably into the various positions which it is designed to occupy, and particularly to prevent 15 the hook 20 thereof from being pushed out too far and remaining out of range when the door rebounds against the impulse received from the dumped material. The weight might be distributed over the entire 20 bar, if desired, by making the bar comparatively wide or thick, but in practice it is deemed preferable to make the bar of relatively slender proportions and add thereto a separate or separable weight 21. Such a 25 weight as 21 is conveniently bolted to the bar, on the back thereof, as shown. A central twist 22, in the bar, helps to relieve the strain on the fastening bolts when the weight is hung in the manner illustrated, 30 and further indicates to the workman how the bar is best applied and its weight located. That is to say, the stress will be partly taken off the bolts by the lower end of the weight 21 resting on the twist 22, when in 35 a substantially vertical position as shown; and the location of the weight above the twist may serve as a guide in applying the attachment to the dump car. It may be noted here that the attachment is not a fixture 40 on the dump-car, where one could rely on always finding it correctly positioned. Its connection therewith is rather transitory. For, although the attachment can remain permanently on the car, it may be 45 thrown on and off, to and from the ground, as well as be transferred from one car to another, all of which is a matter of choice and expediency in the use of this invention.

A hinge link 23 is provided to hold each 50 drop door properly suspended and to assist the bar 18 in coming into effective engagement therewith, when either door is opened. The upper end of the link 23 is pivotally connected to the hopper, as at 24, and its 55 lower end likewise has a pivotal connection 25 with the drop door some distance below the upper edge of the latter. A plurality of links, thus pivoted or hinged, may be employed for hinging each door, the number thereof depending on the width of the door in each instance. As shown in the drawing, 60 each link is bent at an obtuse angle, forming an elbow 26 which is turned outward, and a corresponding bend inward which brings the 65 lower end of the arm, or forearm, under the

upper edge or margin of the door when it is closed. This edge or margin of the closed door, it will be seen, is thereby afforded three supports, including the two pivots 24, 25, and the inner bent portion of the link 70 opposite the elbow, as illustrated both by full and dotted lines in Fig. 1. It will be further observed that when the door is dropped and forced open by the material dumped out of the hopper, its upper and 75 lower edges are swung in opposite directions, the upper edge inward and downward, and the lower edge outward and upward, the pivot 25 being the common center of oscillation. This in a measure divides the 80 weight of the mass to oscillate, by placing part of it on each side of the pivot 25, and facilitates in a corresponding ratio the swinging of that portion of the door which extends below the pivot, through the arc 85 which it is intended to describe. Moreover, owing to the location of the pivot 25, the radius of this arc is shorter than it would be normally, were the door hung from the hopper by means of a single pivot or a plain 90 line of hinges as in ordinary constructions. Now, the sharpness of the arc's curvature is inversely proportional to the length of its radius in any case. Therefore, it is obvious 95 that with the drop-door hinged as herein described, the lower portion thereof below the pivot 25 is swung farther out from the material in the hopper than it would be otherwise, the result being that it is better met by the hook 20, and their engagement is 100 insured.

Having described my invention, what I claim, and desire to secure by Letters Patent of the United States, is:

1. The combination with a receptacle of 105 the kind described, having a side door suspended therefrom by a hinge which allows the door to open outward under pressure of the material discharged from the receptacle, of a holder for said door comprising a portable bar designed to be placed in a substantially vertical position in the path of the door and to be swung out thereby, suspending means at the upper end of said bar adapting it to be thrown into engagement 110 with the receptacle at any desired point along the same, engaging means at the lower end of the bar whereby it is enabled to catch the door by its lower edge, and a weight on the bar adjusted to offset partially the force 115 of impact of the door thereon and cause the bar to swing back in time for its engaging means to grasp the said lower edge of door as the latter starts to return to normal position.

2. The combination with a hopper-like receptacle having a drop side door hung therefrom by a hinge holding the door at some distance below its upper edge, so that when it is opened by the material discharged 130

from the receptacle the door will have its upper and lower parts swinging in opposite directions on a relatively fixed point of oscillation, of a holder for said door including a portable bar designed to be placed in a substantially vertical position in the path of the door pushed out by the discharged material and to receive the impact thereof, an upper hook on said bar adapting it to be thrown at any desired point into engagement with the top portion of the receptacle, a lower hook on the bar arranged to catch

the lower edge of the outswung door, and a weight on the bar partly resisting the force of impact thereon from the door and operating to swing back the bar at a greater rate of speed than that of the door on the rebound. 15

In testimony whereof, I have signed this specification in the presence of two witnesses. 20
HOWARD VAN SCOY.
